(57) **CLAIM**

The ornamental design of a rectangular decorative reflector for vehicle light with multiple light emitting diodes, as shown and described.

DESCRIPTION

FIG. 1 is a perspective view of an embodiment of a rectangular decorative reflector for vehicle light with multiple light emitting diodes showing our new design from the top, front, and right side thereof;

FIG. 2 is a plan view of a top side thereof;

FIG. 3 is a plan view of a bottom side thereof;

FIG. 4 is a plan view of a right side thereof;

FIG. 5 is a plan view of a left side thereof;

FIG. 6 is a plan view of a front side thereof; and,

FIG. 7 is a plan view of a rear side thereof.

The broken lines of FIGS. 1, 2, and 4-6 are used for illustrative purposes and do not form part of the design thereof.
